UNITED STATES PATENT OFFICE.

HUGH T. DYER, OF AUBURN, CALIFORNIA.

ROPE CLAMP.

Application filed May 3, 1927. Serial No. 188,451.

This invention relates to a rope clamp and especially that type which is used for taking up slack or tightening a tent rope with relation to a stake.

5 The object of the present invention is to generally improve and simplify the construction and operation of rope clamps of the character described; to provide a rope clamp consisting of a single piece of wood 10 such as hardwood or the like to which one end of the tent rope may be permanently attached; to provide a slot in one face of the clamp to receive and secure an intermediate portion of the rope so that a bight may be 15 formed about a stake and a pull exerted to tighten and secure the rope; and further to provide retaining means on the clamp whereby the clamp is secured against accidental release when applied to the rope and where- 20 by the clamp may be quickly detached or applied. The invention is shown by way of illustration in the accompanying drawings in which:

Fig. 1 is a plan view of the clamp showing it applied to a tent rope,

Fig. 2 is a perspective view of the clamp.

Referring to the drawings in detail and particularly Fig. 2, A indicates in general the rope clamp forming the subject matter 30 of the present application. The rope clamp may be constructed of any suitable material but preferably of hardwood or the like. It consists of a shank or handle section 2 and a head section 3. The head section is substantially rectangular in cross-section and may be as thick or heavy as desired. In one face thereof is formed a slot 4. This is angularly disposed with relation to a longitudinal axis drawn through the 40 clamp and the slot is under-cut at opposite ends as indicated at 5 and 6 to form overhanging or projecting lugs 7 and 8. The shank or handle end of the clamp is preferably tapered as indicated at 9 and a hole is 45 drilled or otherwise formed in the outer end as indicated at 10 to receive and permanently secure the end of a tent rope such as indicated at 11 (see Fig. 1), a knot 12 being formed on the end of the rope to prevent it 50 from slipping through.

In actual practice the clamp may be used wherever it is desired to tighten or secure a rope, for instance, in connection with clothes lines, tent ropes and the like. In Fig. 1 it 55 may be assumed that the rope 11 is a tent rope. If that is the case, the outer end of

the rope is passed through the hole 10 and the knot 12 is formed. When it is desired to secure the rope with relation to a stake or the like such as shown at 14, the rope is 60 passed around the stake to form a bight 15, and the intermediate portion of the rope is pressed into the slot 4 of the clamp. The clamp is then grasped at a point intermediate the head 3 and the opposite end, and 65 pulled upwardly along the rope. It is at the same time swung to assume the angular position shown in Fig. 1 and it thus bites and secures the rope in the slot. When the angular position is assumed the rope passes 70 through the under-cut portions 5 and 6 or in other words in under the projecting lugs 7 and 8 and the clamp is thus secured against accidental release with relation to the rope 75 regardless of the position assumed.

It should be apparent that a clamp such as here illustrated is exceedingly simple in construction and that it may be quickly released or applied as it is only necessary to form a bight such as shown at 15 and to 80 force the rope into the slot 4 when it is desired to apply the clamp. The clamp when applied is rigidly secured and due to the angular position which it assumes, slippage or release of the rope is positively prevented. 85

While certain features of the present invention are more or less specifically described and indicated, I wish it understood that various changes may be resorted to within the scope of the appended claims; similarly, 90 that the materials and finish of the several parts employed may be such as the manufacturer may dictate or varying conditions or uses may demand.

Having thus described my invention, what 95 I claim and desire to secure by Letters Patent is:—

A device of the character described comprising a member formed of a single piece of comparatively wide flat material of uniform thickness, one end of said member being tapered, the larger end of said member having a slot formed in one face to receive and secure a rope, said slot being arranged laterally of the member and at an angle to its longitudinal axis, a pair of projecting lugs on the member and arranged one at each 100 end of the slot and overlying the latter, said tapered end of the member being formed with an opening therethrough lying in substantially the same plane as the slot. 105

HUGH T. DYER.
